(57) **CLAIM**

The ornamental design for an electric toothbrush bristle pattern, as shown and described.

DESCRIPTION

FIG. 1 is a front elevation view showing the electric toothbrush bristle pattern of my new design;

FIG. 2 is an enlarged view of the head portion of the front elevation view shown in FIG. 1, to more clearly show the detail thereof;

FIG. 3 is a right side elevation view of the electric toothbrush bristle pattern shown in FIG. 1, the left side elevation is a mirror image thereof;

FIG. 4 is an enlarged view of the head portion of the right side elevation view shown in FIG. 2;

FIG. 5 is a top elevation view of the electric toothbrush bristle pattern shown in FIG. 1; and,

FIG. 6 is a front perspective view from the left bottom side thereof.

The body of the electric toothbrush in the above Figures is shown in broken lines for illustrative purposes only and forms no part of the claimed design.
